ARCHERY BOW

Neil W. Tarbell, 654 E. E St., Ontario, Calif.

Filed May 23, 1962, Ser. No. 70,251

Term of patent 14 years

(Cl. D30—1)

FIG. 1 is a rear elevational view of the archery bow showing my new design.

FIG. 2 is a side elevational view thereof as seen from the right of FIG. 1.

FIG. 3 is a front elevational view of the body portion of the bow and shown on a somewhat enlarged scale, with portions broken away for convenience of illustration.

FIG. 4 is a side elevational view of FIG. 3 as seen from the right side thereof.

FIG. 5 is a section taken on the line 5—5 of FIG. 4 and shown on an enlarged scale.

FIG. 6 is a section taken on the line 6—6 of FIG. 3 also to an enlarged scale, and

FIG. 7 is a section taken on the line 7—7 of FIG. 3 and is shown to the same scale as FIGS. 5 and 6.

I claim:

The ornamental design for an archery bow, as shown.
